THOMAS C. GLEASON, OF CHICAGO, ILLINOIS.

DESIGN FOR A CHARM, PIN, FLAG, EMBLEM, BANNER, PENNANT, PILLOW-TOP, OR ARTICLE OF SIMILAR NATURE.

55,560.

Specification for Design. Patented June 29, 1920.

Application filed December 23, 1918. Serial No. 268,111. Term of patent 14 years.

To all whom it may concern:

Be it known that I, THOMAS C. GLEASON, a citizen of the United States, residing at Chicago, in the county of Cook and State of Illinois, have invented a new, original, and ornamental Design for Charms, Pins, Flags, Emblems, Banners, Pennants, Pillow-Tops, or Articles of Similar Nature, of which the following is a specification, reference being made to the accompanying drawing, and forming a part thereof.

The drawing illustrates a pin showing my new design.

I claim:

The ornamental design for a charm, pin, flag, emblem, banner, pennant, pillow top, or article of similar nature as shown.

THOMAS C. GLEASON.
